(57) **CLAIM**

The ornamental design for a flexible hose with tool engagement surface and hose connection/hose fittings, as shown and described.

DESCRIPTION

FIG. 1 is a top plan view of a flexible hose with tool engagement surface and hose connection/hose fittings in accordance with my design;

FIG. 2 is a top, front perspective view thereof;

FIG. 3 is a bottom view thereof;

FIG. 4 is a left side elevational view thereof;

FIG. 5 is a front elevational view thereof;

FIG. 6 is a right side elevational view thereof; and

FIG. 7 is a rear elevational view thereof;

FIG. 8 is a top plan view of a second embodiment of a flexible hose with tool engagement surface and hose connection/hose fittings in accordance with my design;

FIG. 9 is a top, front perspective view thereof;

FIG. 10 is a bottom view thereof;

FIG. 11 is a left side elevational view thereof;

FIG. 12 is a front elevational view thereof;

FIG. 13 is a right side elevational view thereof; and,

FIG. 14 is a rear elevational view thereof.

The broken lines shown represent portions of the flexible hose with tool engagement surface and hose connection/hose fittings that form no part of the claimed design.
